UNITED STATES PATENT OFFICE.

JOSEPH ARDO, OF NEWHALL, WEST VIRGINIA, ASSIGNEE OF ONE-HALF TO
KALMAN HORVATH, OF NEWHALL, WEST VIRGINIA.

MANUALLY-PROPELLED FLYING MACHINE.

Application filed December 30, 1921. Serial No. 525,993.

To all whom it may concern:

Be it known that I, JOSEPH ARDO, citizen of the United States, residing at Newhall, in the county of McDowell and State of 5 West Virginia, have invented certain new and useful Improvements in Manually-Propelled Flying Machines, of which the following is a specification.

This invention relates to a manually pro- 10 pelled flying machine combining both a gas bag and a lifting plane, and it has for an object to provide a simple flying machine of the above type.

A further object is the provision of a 15 novel form of propelling means.

For further comprehension of the invention, and of the objects and advantages thereof, reference will be had to the following description and accompanying drawings, 20 and to the appended claims in which the various novel features of the invention are more particularly set forth.

Fig. 1 of the drawings is a side view of a manually propelled flying machine con- 25 structed according to the invention.

Fig. 2 is a front view thereof.

Fig. 3 is a partial plan view.

Fig. 4 is a detail plan view showing the understructure and part of the propelling 30 mechanism.

Fig. 5 is an axial sectional view of the fly- 35 wheel gear of the propelling mechanism.

Fig. 6 is a partial face view, certain exterior parts being broken away.

Fig. 7 is a face view of one form of propeller.

Fig. 8 is an enlarged section on the line 8—8 of Fig. 7.

Fig. 9 is an axial sectional view of the 40 other form of propeller.

In constructing my improved flying machine I provide a frame whose base is formed by a platform 10 mounted, by means of struts 11, on wheels 12. On this platform is 45 a seat 13 for the operator. Extending rearwardly from the seat is a fixed vertical fin 14 in which is hinged a rudder 15. The rudder 15 is adapted to be operated by suitable connections indicated generally at 16. A fixed 50 horizontal tail 17 is also provided and is provided with a movable elevator 18 operated by suitable means.

Extending above the platform is a flat frame piece 20 which supports, by means of struts 21, a flooring 22 on which is mounted 55

a gas bag 23 held in place by bands 24. Projecting rigidly outward from opposite sides of the machine are a pair of wings or planes 25 provided with suitably operated ailerons 26 for maintaining lateral stability. 60

For propelling the flying machine I provide a pair of helical propellers supported by brackets 31 depending from the wings 25. These propellers each comprise a pair of blades 30 fixed on the outer ends of short radial shafts 32 whose inner ends are set in sockets in a T-head 33 on the main propeller shaft 34. Angular adjustment of these blades is effected by means of a large bevel gear 35 loosely mounted on shaft 34, 70 and meshing with bevel pinions 35^a on the radial shafts 32.

Formed in the hub 35^a of gear 35 is a spiral slot 36 in which engages a pin 37 on a sleeve 38 feathered as at 38' on shaft 34 75 and projecting into the hub 35^a. A second sleeve 40 encircles the shaft 34 adjacent the sleeve 38 and has a feather connection 41 with the hub of the bearing bracket 31. The sleeve 38 is normally urged toward the sleeve 80 40 by a stiff expansion spring 39. This sleeve 40 has spiral rack teeth 42 formed on one side thereof and engaged by a worm gear 43 fixed on a shaft 44 suitably journaled in the bracket 31. On shaft 44 is also fixed a pulley 45 over which is looped a belt 46 engaging also over a double pulley 47 fixed on a shaft 48 extending to a point adjacent the seat 13 and provided with a hand-wheel 49 for turning purposes. When pulley 47 is 85 rotated sleeves 40 and 38 are moved longitudinally of the shaft 34 and in consequence of the engagement of pin 37 in slot 36 the bevel gear 35 is partially rotated on shaft, 90 rotating in turn the bevel pinions 35^a and 95 changing the angles of the propeller blades.

As will be understood there are a pair of shafts 34 and to rotate the same their forward ends are connected by bevel gears 50 to a transverse shaft 51 having a spur pinion 52 fixed thereto midway between its ends. This spur pinion engages with a large gear 53 loose on a stub shaft 54 suitably mounted in an enclosing frame element 55. Fixed on gear 53 is a pawl 56 pressed by a spring 57 against a ratchet wheel 58 fixed on shaft 54. Shaft 54 has also fixed thereto a pair of crank arms 60 to which are connected rods 61 which extend rearwardly to connect to operating levers 62 fulcrumed as at 63 on 110

2
the platform 10, the levers having pedal elements 65 mounted thereon on which the operator's feet are placed, one of the levers having an upward extension 62' which may be grasped by the operator. The large gear is adapted to act as a flywheel and may be constructed as shown in Figs. 5 and 6 with a pair of spaced radial plates 53' between which a series of weights such as 66 are located. The machine is driven by reciprocating the levers 62, the pawl and ratchet connection 56, 58 causing the gear 53 to rotate in one direction, the weighted construction of the gear causing it to rotate continuously.

10 The propellers 30 are mounted on the front ends of the shafts 34, which have other propellers 70 mounted on their rear ends and comprising a pair of blades fixed on the outer ends of a pair of radial shafts 71 journaled in a T-head 72 on the rear end of shaft 34. Fixed to a bracket 73 which supports the rear end of shaft 34 is a bevel gear 75 meshing with a pair of bevel pinions 76 on the shafts 71. As will be apparent, when shaft 34 rotates the propeller blades 70 are also caused to rotate on their own axes.

20 The gas bag is of sufficient capacity to support the machine alone, without the driver, the action of the air on the wings causing the machine to rise with the driver when the propellers are rotated, the machine descending to the ground when the propellers stop.

30 Having thus described my invention what I claim as new and desire to protect by Letters Patent of the United States is as follows:

35 1. In a flying machine, a propeller comprising a pair of radial blades, a propeller shaft, a T-head fixed on said shaft and having said blades rotatably mounted thereon, a bevel gear loosely encircling said shaft, bevel pinions fixed to said blades and meshing with said bevel gear, a sleeve feathered on said shaft and having a pin and spiral groove engagement with said bevel gear, and means for adjusting said sleeve longi-

tudinally of said shaft, said means comprising a second sleeve loose on said shaft and having a feather connection with a fixed part 50 and bearing at one end said first sleeve, a spring bearing against the other end of said first sleeve.

2. In a flying machine, a propeller comprising a pair of radial blades, a propeller shaft, a T-head fixed on said shaft and having said blades rotatably mounted thereon, a bevel gear loosely encircling said shaft, bevel pinions fixed to said blades and meshing with said bevel gear, a sleeve feathered 60 on said shaft and having a pin and spiral groove engagement with said bevel gear, and means for adjusting said sleeve longitudinally of said shaft, said means comprising a second sleeve loose on said shaft and having a feather connection with a fixed part 65 and bearing at one end against one end of said first sleeve, a spring bearing against the other end of said first sleeve, helical rack teeth on said second sleeve, and a worm gear 70 meshing with said rack teeth.

3. In a flying machine, a propeller comprising a pair of radial blades, a propeller shaft, a T-head fixed on said shaft and having said blades rotatably mounted thereon, 75 a bevel gear loosely encircling said shaft, bevel pinions fixed to said blades and meshing with said bevel gear, a sleeve feathered on said shaft and having a pin and spiral groove engagement with said bevel gear, and means for adjusting said sleeve longitudinally of said shaft, said means comprising a second sleeve loose on said shaft and having a feather connection with a fixed part and bearing at one end against one end of said 85 first sleeve, a spring bearing against the other end of said first sleeve, helical rack teeth on said second sleeve, a worm gear meshing with said rack teeth, and pulley and belt means for rotating said worm gear. 90

In testimony whereof I have affixed my signature.

JOSEPH ARDO,
